[57] CLAIM

[21] Appl. No.: 833,598

The ornamental design for a cargo restraint clip, as
 shown.

[22] Filed: Sep. 15, 1977

DESCRIPTION

[51] Int. Cl. .... D8—08
 [52] U.S. Cl. D8/382; D8/394
 [58] Field of Search 248/499, 261; 52/220;
 254/191; D8/354, 367, 371, 382, 394, 395

FIG. 1 is a perspective view of a cargo restraint clip
 embodying our invention;
 FIG. 2 is an end elevational view of FIG. 1 somewhat
 reduced in size;
 FIG. 3 is a top plan view of FIG. 2; and
 FIG. 4 is a left end view of FIG. 2.
